Fig. 3

To all whom it may concern:

Be it known that I, Benjamin Fox, a citizen of the United States and a resident of Philadelphia, in the county of Philadelphia and State of Pennsylvania, have invented a new, original, and ornamental Design for Electrical Connector, of which the following is a specification, reference being had to the accompanying drawing, forming a part hereof.

In the drawing:

Fig. 1 is a perspective view of an electrical connector, showing my new design.

Fig. 2 is an enlarged sectional view taken along the line 2—2 of Fig. 1.

Fig. 3 is an enlarged sectional view taken along the line 3—3 of Fig. 1.

The dominant feature of my design resides in the portion shown in full lines. The surface of the connector opposite to that shown in Fig. 1 is identical to that of Fig. 1.

I claim:

The ornamental design for an electrical connector, as shown and described.
